(57) **CLAIM**

I claim the ornamental design for a door support hinge, as shown and described.

DESCRIPTION

FIG. 1 is a frontal perspective view of the door support hinge.

FIG. 2 is a front elevation view.

FIG. 3 is a left side elevation view.

FIG. 4 is a top plan view.

FIG. 5 is a right side elevation view.

FIG. 6 is a rear elevation view.

FIG. 7 is a bottom plan view; and,

FIG. 8 is a top plan view with the door support hinge in an open position.

The broken lines represent environment and form no part of the claim.
